STAND FOR MAKING AND DISPLAYING CUSTOM-MADE LIPSTICKS

Joseph A. Danilek, Garden City, N.Y., assignor to Mary Chess, Incorporated, New York, N.Y., a corporation of Delaware

Filed Nov. 25, 1959, Ser. No. 58,464

Term of patent 14 years

(Cl. D80—9)

Fig. 1.

Fig. 2.

Fig. 3.

Fig. 4.

Fig. 5.

Fig. 1 is a front perspective view taken from the top and right side of a stand for making and displaying custom-made lipsticks embodying my new design;

Fig. 2 is a front elevational view thereof;

Fig. 3 is a right side elevational view thereof;

Fig. 4 is a top plan view thereof; and

Fig. 5 is a rear elevational view thereof, the lipsticks being shaded to indicate contrasting color.

The broken line representation of a pan in Fig. 1 is for illustrative purposes only.

I claim:

The ornamental design for a stand for making and displaying custom-made lipsticks, as shown and described.
